(57) CLAIM

The ornamental design for a combination spray and pour nozzle, as shown and described.

DESCRIPTION

FIG. 1 is a perspective view of a first embodiment of a combination spray and pour nozzle showing my new design as seen from the top and front, the broken lines showing a bottle are for illustrative purposes only and do not form part of the claimed design;

FIG. 2 is a side elevation view thereof, the opposite side being a mirror image of that shown;

FIG. 3 is a front elevation view thereof;

FIG. 4 is a rear elevation view thereof;

FIG. 5 is a top plan view thereof;

FIG. 6 is a perspective view of a second embodiment of a combination spray and pour nozzle showing my new design as seen from the top and front, the broken lines showing a bottle are for illustrative purposes only and do not form part of the claimed design;

FIG. 7 is a side elevation view thereof, the opposite side being a mirror image of that shown;

FIG. 8 is a front elevation view thereof;

FIG. 9 is a rear elevation view thereof; and,

FIG. 10 is a top plan view thereof.
